United States Patent Office.

ANDREW C. HARTSOCK, OF DOUGLAS, ILLINOIS.

Letters Patent No. 80,171, dated July 21, 1868.

IMPROVED MILLSTONE-DRESS.

The Schedule referred to in these Letters Patent and making part of the same.

TO ALL WHOM IT MAY CONCERN:

Be it known that I, ANDREW C. HARTSOCK, of Douglas, in the county of Knox, and State of Illinois, have invented a new and useful Improvement in Millstone-Dress; and I do hereby declare the following to be a full and correct description thereof, sufficient to enable those skilled in the art to which my invention appertains to fully understand and construct the same, reference being had to the accompanying drawings, which make part of this specification, and in which—

Figure 1 is a plan of the face of the bed-stone.

Figure 2 is a plan of the face of the runner.

Figure 3 is a plan of the central portion of the bed-stone.

Figure 4 is a cross-section of fig. 2, and

Figure 5 is a cross-section of fig. 1.

Like letters of reference indicate like parts in the several figures of the drawings.

In the operation of grinding grain in mills it is a proposition well settled by practice that the amount ground is always in proportion to the area of grinding-surface and the number of cutting-edges employed for such purpose. In the ordinary dress of millstones different sizes of grinding-disks are used. The lesser size will of necessity have to be revolved more rapidly, in order to bring the same amount of grinding-surfaces and cutting-edges in contact with the grain being ground, in the same length of time as would be in disks of greater diameters and less revolutions.

In mills having grinding-disks of small diameters, in order to carry out this proposition, the revolutions are so rapid that many bad effects follow, such as heating the spindle and causing expansion of the same, necessitating constant care in adjusting the stones, and in the heating of the grinding-disks themselves, causing much of the grain to escape from between the stones or disks imperfectly ground, and all overheated, to the manifest injury of all the meal so ground.

In order to produce grinding-disks of small diameter, having the grinding capacity of those of a greater diameter, without any of the defects enumerated as belonging to mills of small diameter, is the object of this invention; and it consists in so constructing the dress of the stone, that it causes the cutting and grinding of the grain to be done upon the edges and sides of peculiarly-formed teeth, instead of upon plane surfaces and straight or circular cutting-edges, as in the ordinary method of millstone-dress.

A, in the drawings, represents the distributing-teeth, near the centre of the disk or stone, so formed that, as the grain is fed through the eye, it comes in contact with and is distributed by them into the radial furrows *b* and circular furrows *a*.

B are the grinding-teeth, placed in circles concentric with the eye, and separated by radial furrows *b*, and from the next concentric series by furrows *a*.

a a are furrows, in circles, and concentrically related to each other, the inner, or that having the smallest diameter, being the deepest, and each successive or larger in diameter is less in depth.

b b are short radial furrows, that cut across the concentric rings, and separate such rings into teeth *B*, having a sharp inclined cutting-edge, formed by the angular direction at which furrow *b* is cut.

This furrow is, by the tooth in the next concentric ring, interrupted in its continuance, which causes the grain to be deflected and traverse the furrow *a* to the next radial or cross-furrow *b*.

The two stones or grinding-disks are constructed in such manner that the teeth *B* of one disk fit into the furrow *a* of the other.

The construction of this dress is such that the teeth of the inner or smaller circle have the same or nearly the same area of grinding-surface and extent of cutting-edges as the larger in diameter and greater in number of the next circle, by reason of their greater projection from the bottom of the furrow.

It will also be seen that the cutting-edges of the teeth are of such shape that, as the teeth in the two disks

approach and pass, the cutting of the grain is made by what is termed a "shear cut," thus tending to keep the cutting-edges in condition longer, and doing more work with the same power than in the ordinary dress of millstones. I am aware that coffee-hullers and coffee-mills have had the teeth upon their scouring and grinding-surfaces in irregular or zigzag form, and in concentric circles, in order to obstruct the direct passage of the coffee-grains from the mill without a complete operation, the difference between such a construction of grinding-surfaces and my improvement being that the teeth all project alike from the bottom of the furrow or plane of the disk. Nor is the cutting-edge of the teeth the same as mine. In my improvement the teeth in the different circles vary in projection, and have a different form of cutting-edge, as the teeth on the two disks, when in operation, have a very different angle at which the cutting-edge is formed and comes in contact with the grain, and the difference in the size and area of the grinding-surfaces of the teeth in different circles of the several series.

Having thus described my invention, and the difference between it and other inventions in like machines, what I claim as new, and desire to secure by Letters Patent, is—The millstone-dress, composed of the distributing-teeth A, grinding-teeth B, circle-furrows *a*, and short angular furrows *b*, constructed and arranged in relation to each other, in the manner and for the purpose substantially as described.

To the above I have signed my name, this 26th day of May, 1868.

A. C. HARTSOCK.
